UNITED STATES PATENT OFFICE

FRANSISCUS C. J. DE BOTH, DECEASED, BY JACOBUS J. D. DE BOTH, ADMINISTRATOR, OF
NYMEGEN, NETHERLANDS; JOHANNES PETRUS MATHEUS DE BOTH NOW ADMINIS-
TRATOR OF SAID FRANSISCUS C. J. DE BOTH, DECEASED

MEANS FOR SCOURING AND POLISHING ASPHALTIC PLATES

Original application filed June 16, 1927, Serial No. 199,314. Divided and this application filed April 9, 1928. Serial No. 268,697.

The present invention is a division of application for patent filed June 16th 1927, Serial #199,314, upon method and apparatus for making and method of applying asphalt plates.

The present invention, in its broad aspect, has to do with improvements in means and methods of scouring and polishing bitumastic, asphaltic, asphaltic-granito, and the like, plates for use as floor, aisle, wall or other surface coverings. Asphaltic or bitumastic, or asphaltic-granito plates, such as are operated upon by this present apparatus may be made after the method described in Patent #1,643,059, granted September 20th 1927, and when applied form a desirable, wear resisting and durable surface which is free from dust, and which is both moisture and weather proof and of pleasing and artistic aspect and appearance. In ordinary practice the materials forming the asphaltic or bitumastic mass from which the plates are made are preferably compounded according to two formulas; the first, involving the use of ground asphalt rock and 15 to 20 per cent of bitumen; and the second, a mixture of asphalt mastic (a commercial product) and a per cent of bitumen and sand to attain the desired consistency. When it is desired to form asphaltic-granito plates from 15 to 20 per cent very fine (about 00 degrees comminution) marble chips (without dust) are added to the mass. It is especially in the forming and scouring and polishing of asphaltic-granito plates that the present invention is directed. The scouring machine comprises a table, a reciprocating element and a ballast element; and in operation, asphaltic-granito plates are transported (after being cut) to the scouring machine and a layer of plates laid bottom side or black side up (the top side bearing the addition of marble chips); another layer is superposed on the first layer with the bottom or black side down, the ballast elements are then lowered by a suitable winch and are fastened by a punching instrument to prevent shifting sand is now spread on the assembly and the whole is sprinkled with water whereupon the device

is started and reciprocated at about 60 R. P. M. of the power element (not shown) and this operation is continued until the marble chips show through the plates presenting a smooth and pleasing appearance. 55 During the scouring the attendant adds sand and water in proper quantities to effect expeditious production of the plates, and after the operation the plates are thoroughly rinsed in water. Any black stains upon the plates after the scouring may be removed by a polishing machine after the plates are laid upon a floor or the like. 60

Among the principal objects and advantages of the present invention may be briefly defined the following; first, the scouring table is formed largely of channel iron and plate metal which is obtainable on the open market and therefore facilitates the manufacture of the machine; second, novel means are provided for blocking up and adjusting the plates on the table; third, the ballasting device is formed in sections which may be taken down and the like, and; fourth, the scouring device is simple in construction, 70 75 and positive and practical in operation.

With these and other objects in view the invention consists in the novel steps and combinations of steps constituting the method, and in the novel details of construction and arrangements of parts constituting the apparatus, as will be more fully disclosed hereinafter and particularly pointed out in the claims. 80

In the drawings wherein is illustrated the preferred embodiment of the invention;—

Figure 1 is an isometric view of the ballasting device;

Figure 2 is a side, assembly view, of the 90 scouring apparatus;

Figure 3 is a fragmentary top plan view of the scouring device;

Figure 4 is a transverse sectional view of the device taken through the member 91 on one side and the member 9 on the other and shows the details of the table and its base;

Figure 5 is a detail view of the plate adjusting and blocking device, and 100

Figure 6 is a detail view of a modified form of plate adjusting and blocking device.

In the drawings, like characters of reference are used throughout the several views to designate like or similar parts.

In forming asphaltic-granito plates marble chips are sprinkled over the tops thereof and it is necessary to grind or scour the same to form an even and pleasing surface. Other plates besides asphaltic-granito plates are adapted to be operated upon by the device, but these are used for the sake of illustration, and especially to bring out the application of the method.

The device comprises a relatively massive base (1) on which the stringers (channel-iron) (2) are bolted as at (3). Upon the stringers is mounted the table (4) which is transversely reinforced as at (5). The operative, or movable element, of the machine is a rectangular plate metal form or scouring member (6), one end of which is provided with a coupling (7) for the end of the pitman or crank (8) of a power element (not shown) which is designed to reciprocate the member (6) at about 60 R. P. M. of the power element when in action. The form or scouring member (6) is slidably mounted as at (9) on rods (10) carried by supports (11) on the bed, floor or table (4). The asphaltic-granito plates, designated (12) and (13), are placed on the table (4). Plate 12 is properly blocked against shifting by the clamp shown in Figures 5 and 6, and which comprises a wooden block (14), a follower (15) and a screw actuating means (16) engaging the frame of the floor and having a hand wheel (17). The follower (15) works on the smooth shank (18) of the screw (19) which carries the hand wheel (17), and a washer (20) is preferably placed between the hand wheel and follower. The block engaging, and over-bent portion (21) of the follower works in a recess (22) in the edge of the table, and sets below the stock so as to be out of the way, although it is above the top surface of the table. An alternate form is shown in Figure 6 wherein the follower (23) is arranged on channel member (24) and has a hand wheel (25) to adjust the block (26); in this case the follower is above the block (26) but outside the periphery of the table, and the channel member is recessed as at (27) to allow movement of the follower toward the table. In practice the layer of plates (12) are placed bottom or black side up on the table, and clamped immovably in place by the followers shown in Figures 5 and 6, thereupon another layer (13) is superposed thereon placed bottom or black side down. This latter layer is free to slide on the layer (12), and sand is sprinkled or placed between the two layers. The ballast element is then lowered

upon the layer of plates 13. The ballast element fits between the side and end rails of the rectangular scouring member 6 and comprises a plurality of plates (28) attached each to supporting frame members (29) of L-iron, spacers (30) being used, and chains (31) connect the frame members to a winch (not shown) for raising and lowering the same. After the sand has been placed between the layers of plates (12) and (13) they are sprinkled with water so that the sand is wet. The ballast having been applied and the scouring frame set in motion, the layer (13) is rubbed across the layer (12) and the operation is kept up until the proper finish is obtained.

It is obvious that those skilled in the art may vary the details of construction as well as the arrangements of parts without departing from the spirit of the invention, and therefore it is not desired to be limited to the foregoing disclosure except as may be required by the claims.

What is claimed is:—

1. In an apparatus for scouring plates, a ballasting member for the plates comprising angle iron frame members, and plurality of ballasting plates each connected to the frame members, and attaching means engaging the frame members for lifting the ballasting assembly.

2. Apparatus for scouring asphaltic plates comprising a base, relatively parallel stringers fixed to the base, a reinforced table member fixed upon the stringers, a plurality of supports carried by the sides of the table, a frame slidably mounted in the support above the table, means including a follower and blocks bearing against a layer of plates on the table for holding the plates in place thereon beneath the frame, a ballasting element in the sliding frame and composed of a plurality of connected plates for engaging a layer of plates disposed on the first layer, and means for reciprocating the frame to cause the latter plates to move on the fixed layer of plates thereby to scour the plates.

3. Apparatus for scouring asphaltic plates comprising a base, relatively parallel stringers fixed to the base, a reinforced table member fixed upon the stringers, a plurality of supports carried about the sides of the table, rods engaging the supports, and carried by a frame for slidable movement, whereby said frame may be reciprocated back and forth over the table, means including a screw follower and blocks bearing against the layer of plates on the table for holding the plates in place thereon beneath the frame, a ballasting element in the sliding frame and comprising plates and means for attaching said plates together to form a unit, said ballasting element bearing against a layer of plates disposed on

the first layer of plates and means for reciprocating the frame to slide the top layer over the lower layer of plates thereby to scour the plates.

5 In testimony whereof, I affix my signature hereunto.

FRANSISCUS C. J. DE BOTH,

Deceased,

By JACOBUS J. D. DE BOTH,

Administrator.
